UNITED STATES PATENT OFFICE.

WILLIAM Q. TOLMAN, OF NEW BEDFORD, MASSACHUSETTS, ASSIGNOR TO
THE PAIRPOINT MANUFACTURING COMPANY, OF SAME PLACE.

DESIGN FOR A BOX-COVER.

SPECIFICATION forming part of Design No. 22,818, dated October 3, 1893.

Application filed January 18, 1893. Serial No. 458,839. Term of patent 7 years.

To all whom it may concern:

Be it known that I, WILLIAM Q. TOLMAN, a citizen of the United States, residing at New Bedford, in the county of Bristol and State of Massachusetts, have invented and produced a new and original Design for a Box or other Cover, of which the following is a specification, reference being had to the accompanying drawing, showing my new design.

5 The leading feature of my design consists in a border inclosing a name space or space for an inscription near one corner of which are diamond shaped figures.

A is the cover and B an ornamental border inclosing a space for a name or inscription. At 15 one corner of this space is a diamond shaped figure D composed of four small diamond shaped figures so arranged as to form a large diamond shaped figure.

What I claim is—
20 The design for a box or other cover herein shown and described.

WILLIAM Q. TOLMAN.
